UNITED STATES PATENT OFFICE.

OZRO C. LANPHEAR, OF GALESBURG, ILLINOIS, ASSIGNOR TO GRAND COUNCIL OF DELTA-DELTA-DELTA FRATERNITY.

DESIGN FOR A BROOCH OR SIMILAR ARTICLE.

No. 40,134.

Specification for Design.

Patented July 13, 1909.

Application filed May 8, 1909. Serial No. 494,942. Term of patent 14 years.

To all whom it may concern:

Be it known that I, OZRO C. LANPHEAR, a citizen of the United States, and a resident of Galesburg, in the county of Knox and State of Illinois, have invented a new, original, and ornamental Design for a Brooch or Similar Article, of which the following is a specification, reference being had to the accompanying drawing, forming part thereof.

Figure 1 is a plan view of a brooch, showing my design; and Fig. 2, an edge elevation, seen from the closed side of the crescent.

I claim:—

The ornamental design for a brooch or similar article, as shown.

OZRO C. LANPHEAR.
